UNITED STATES PATENT OFFICE.

ALBERT E. CALDWELL, OF ERIE, PENNSYLVANIA, ASSIGNOR TO CONTINENTAL RUBBER WORKS, OF ERIE, PENNSYLVANIA, A CORPORATION OF PENNSYLVANIA.

DESIGN FOR A TIRE TREAD.

Application filed March 10, 1923. Serial No. 5,428. Term of patent 7 years.

To all whom it may concern:

Be it known that I, ALBERT E. CALDWELL, a citizen of the United States, residing at Erie, in the county of Erie and State of Pennsylvania, have invented a new, original, and ornamental Design for a Tire Tread, of which the following is a specification, reference being had to the accompanying drawing, forming a part thereof.

Fig. 1 is a plan view of the tire tread.
Fig. 2 a section on the line 2—2 in Fig. 1.

I claim:—

The ornamental design for a tire tread, as shown.

ALBERT E. CALDWELL.
